UNITED STATES PATENT OFFICE.

VERNON DURBIN, OF BROOKLINE, MASSACHUSETTS, ASSIGNOR TO THE HOLTZER-CABOT ELECTRIC COMPANY, OF ROXBURY, MASSACHUSETTS, A CORPORATION OF MASSACHUSETTS.

FIRE-ALARM APPARATUS.

Application filed June 14, 1918. Serial No. 239,929.

To all whom it may concern:

Be it known that I, VERNON DURBIN, a citizen of the United States, residing at Brookline, in the county of Norfolk and 5 State of Massachusetts, have invented certain new and useful Improvements in Fire-Alarm Apparatus; and I do hereby declare the following to be a full, clear, and exact description of the invention, such as will 10 enable others skilled in the art to which it appertains to make and use the same.

The present invention relates to an improvement in fire alarm apparatus.

Fire alarm apparatus of the type to which 15 the present invention relates commonly comprise three circuits: a main alarm circuit, a local alarm circuit, and a disarrangement signal circuit. The main alarm circuit is in connection with the fire department of the 20 city or town; the local alarm circuit is in connection with signal bells in the building in which the apparatus is placed; and the disarrangement signal circuit is in connection with a disarrangement bell usually located 25 in the janitor's office. Fire alarm apparatus of this character is usually so constructed that when in case of a fire the main alarm circuit is thrown into operation to notify the fire department, the local alarm 30 circuit and the disarrangement signal circuit are also thrown into operation to give the necessary local warning; but when in the case of a test drill it is not desired to notify the fire department, only the local 35 alarm circuit and the disarrangement signal circuit are thrown into operation. In both cases the disarrangement signal circuit is operated to indicate that the apparatus is not in its normal condition. One object of 40 the invention is to improve upon the construction and arrangement of the parts of a fire alarm apparatus of the above described type, to the end that greater efficiency in operation may be secured. A further object 45 of the invention is to improve upon the construction and arrangement of those parts of the apparatus which support the circuit operating means in position on the wall of the building in which the apparatus is located, 50 to the end that the work of installing the apparatus may be more speedily and effectively accomplished than has heretofore been possible. To the accomplishment of these objects and such other objects as are incidental 55 thereto, the present invention consists in the

improved fire alarm apparatus hereinafter described and particularly pointed out in the appended claims.

The preferred form of the invention is illustrated in the accompanying drawings in which Figure 1 is a front elevation of the fire alarm apparatus with the door open; Fig. 2 is a detail showing a front elevation of the lever device connected with the glass panel; Fig. 3 is a side elevation of the parts shown in part 2; Fig. 4 is a section taken along the line 4—4 of Fig. 2 looking in the direction of the arrow; Fig. 5 is a section showing particularly the mounting of the outlet box in a wall and the manner of connecting the cover therewith; and Fig. 6 is a side elevation of the casing for enclosing the circuit operating means.

The fire alarm apparatus of the present invention comprises in general an outlet box 10, a cover 11 having a door 12 hinged thereon, and a casing 13 for enclosing and supporting the means for operating the various circuits. The outlet box 10 is adapted to be received in a recess 14 of a wall 15 of the building in which the apparatus is installed. The casing 13 is supported within the outlet box, and the cover 11 is placed in position with its lower rim 16 against the face 17 of the wall 15 to cover over the other parts 80 and render them inaccessible except to those using the apparatus. The manner of mounting the outlet box and of securing the cover 11 and casing 13 thereto forms a feature 85 of the invention, and will be particularly described hereinafter.

The fire alarm apparatus embodying the present invention contemplates the provision of operating mechanism by which three independent circuits are controlled, to-wit, the main alarm circuit, the local alarm circuit, and the disarrangement circuit. These circuits are preferably controlled in the manner and by the construction illustrated and described in my Patent No. 1,261,745 of 95 April 2, 1918, to which reference is made for disclosure and description of the circuit operating mechanism in detail. The greater part of this circuit operating means is enclosed within the casing 13 shown in Fig. 6. Through two holes in the bottom of this casing extend the wires 19 which are connected 100 with the various circuits controlled by the apparatus. On a rotatable shaft 20 projecting from the top of the casing is a lever 21, 110

a movement of which under certain conditions operates only the local alarm circuit; and a movement of which under other conditions operates both the local alarm circuit and the main alarm circuit. Also projecting from the top of the casing 13 are two plungers 22 and 23 connected respectively with the disarrangement signal circuit and the main alarm circuit. When both plungers 10 are pressed down as shown in Fig. 3 both the circuits they control are held inoperable. When, however, the plungers are permitted to rise under certain conditions of 15 operation of the fire alarm apparatus, the disarrangement signal circuit is thereby thrown into operation and the main circuit is rendered operable. The plunger 22 is pressed down to hold the disarrangement signal circuit inoperable when the door 12 is 20 shut against the cover 11, and a glass panel 26, by which the lever 27 is held in normal position, which is the position shown in Fig. 1, is in place. The plunger 23 is pressed down to hold the main alarm circuit inoperable when the glass panel is in place. 25 A clear understanding of the connections between the operating lever 21, plungers 22, 23, and the three separate circuits, namely, the main alarm, local alarm, and disarrangement circuits, may be had by reference to the above mentioned patent, bearing in mind that the plungers 22, 23 are constructed similar to and operate in the same manner as the plungers 89, 90 of said patent shown 30 in detail in Figs. 8, 9, 10, 11 and 12 thereof. The operating lever 21 corresponds to the lever 26 of said patent. From a consideration of the above mentioned patent it will be observed in the present construction that 35 when both plungers 22, 23 are pressed down, the main alarm circuit and the disarrangement signal circuit are both held inoperable, and when the plunger 22 is permitted to rise the disarrangement circuit is operated; and 40 when the plunger 23 is permitted to rise the main alarm circuit is rendered operable. 45

The lever 21 for actuating the local alarm circuit and main alarm circuit operating means has two handles 29 and 30. The 50 handle 29 is located on the free end of the lever 21 and extends beyond the edge 25 of a glass holding plate 31 mounted on the casing 13, so that when the door 12 is open, the handle 29 may be reached to manipulate 55 the lever 21 to sound the local alarm only. When the door is shut against the casing 11 the handle 29 cannot be reached. The handle 30 is located at the middle of the lever 21 and is normally rendered inaccessible by 60 the glass panel 26, which is held in place on the glass holding plate 31 by lugs 32. In a case of fire the glass panel 26 is broken so as to render the main alarm circuit operable — a movement of the lever 21 by the handle 65 30 then throws the main alarm circuit into

operation to notify the fire department. The glass panel holds the main alarm circuit normally inoperable by its engagement with a pin 33 fixed in the short arm of the lever 27. A spring 34 presses the pin 33 against the adjacent edge of the glass panel. With this disposition of the parts and with the door 12 shut, a two part plunger-holding lug 35, carried by the lever 27, is positioned transversely of the plungers 22 and 23 and holds them down as shown in Fig. 3. When the glass panel is not in place, as when it is broken, the spring 34 acts to turn the lever 27 so as to bring the two part lug 35 lengthwise of and half way between the plungers 22 and 23. These being spring pressed, thereupon rise into contact with the underside 36 of the hub 37 of the lever 27, thereby throwing the disarrangement signal circuit into operation and rendering the main alarm circuit operable. The hammer 40 is provided to facilitate the breaking of the glass panel in case of fire.

It is necessary that the disarrangement signal circuit be operated when the door 12 is open to permit a manipulation of the lever 21 to sound the local alarm when a test drill is given. The plunger holding lug 35 is accordingly made in two parts—one part 38 (Fig. 4) of which is fixed on the lever 27 and engages with the plunger 23, and a second part 39 of which is movable and engages with the plunger 22. The lever 27 is rotatably held on the plate 31 by a threaded sleeve 41 screwed into a boss 42 on the underside of the plate 31. The movable lug 39 is fixed to a rod 43 slidably received in the sleeve 41. A cap 44 is screwed onto the projecting end of the rod 43 and is arranged to be engaged by the underside of the door 12 so as to thereby hold the lug 39 down against the plunger 22. The lug 39 is held from turning by a pin 45 which slides in a hole in the hub of the lever 27. When the door is open the plunger 22 is free to push the lug 39 upwards, thereby operating the disarrangement signal circuit.

From the foregoing description it will now be understood that when the door is shut and the glass panel is in place, the lever 21 being inaccessible and the plungers being held down, the circuit operating means is thereby held inoperative. When, however, the door is open, the disarrangement signal circuit is thereby thrown into operation and the local alarm circuit is made operable by exposing the handle 29 of the lever 21. And when the glass panel is not in place, the disarrangement signal circuit is thrown into operation and both the local alarm circuit and the main alarm circuit are rendered operable; the latter condition obtaining whether the door is shut or open.

The outlet box 10, as before stated, is set in a recess 14 sunk in the wall 15 of the

room in which the fire alarm apparatus is placed. This outlet box is closed at its rear end and is open at its front end, as clearly appears from Fig. 5. Conduit pipes for receiving the circuit wires are screwed into the side walls of the outlet box. Secured to the inner periphery of the outlet box are four adjustable supports 48. These supports 48 are provided with elongated slots 49 so that they may be moved lengthwise of the outlet box, and are fastened to the outlet box in adjusted position by cap screws 50. On the upper or front end of each support 48 are two lugs 52 for supporting the cover 11. Each lug 52 is provided with a pin 53 adapted to be received in holes 54 in the cover. The cover is held in place by screws 55 which pass through holes in the cover and are screwed into the outlet box. Projecting inwardly from the upper end of each support 48 is a casing-supporting lug or shelf 56 upon which the casing 13 rests and to which it is secured.

When the apparatus is installed, the outlet box is set in a recess sunk in the wall of the room in which the apparatus is to be placed. The supports 48 are then loosely attached to the outlet box and extend outwardly therefrom so that the pins 53 on the lugs 52 thereof may be received in the holes 54 in the cover 11. The cover is then pushed toward the wall until the rim 16 thereof contacts with the wall. The screws 50 are then tightened to hold the supports in place. The cover is then taken off, and the casing 13 is next secured to the inwardly projecting shelves 56 on the supports; and then finally the cover is again placed so that the pins 53 of the lugs 52 are received in the holes 54 of the casing, after which the cover is secured in place by screws 55. The wires 19 are, of course, attached to their proper terminals before the casing 13 is secured to the shelves 56. The apparatus is now in condition for operation. By reason of this construction and arrangement of parts it will be observed that the cover on which the door is hinged, and the casing for containing the circuit operating means, are supported on the outlet box mechanically independent of each other. The upper surface of the shelves 56 are at a fixed distance from the outer ends of the lugs 52, so that the casing 13 always occupies a fixed distance from the inside of the cover when the latter is shut. Consequently the cap 44 is always pushed down the requisite distance by the door, when the latter is shut, to hold the plunger 22 at the limit of its downward movement to hold the disarrangement signal circuit inoperative.

Having thus described the invention what is claimed as new is:

1. A fire alarm apparatus having a main alarm circuit, a local alarm circuit, and

means for controlling the operation of said circuits including an outlet box provided with a door, a stationary glass panel mounted within the box independently of the door, means for operating the local alarm circuit, and means operatively connected with the stationary glass panel for normally rendering the main alarm circuit inoperative when the local alarm is operated and for permitting operation of the main alarm circuit with the local alarm circuit when the stationary glass panel is broken.

2. A fire alarm apparatus having a main alarm circuit, a local alarm circuit, and means for controlling the operation of said circuits including an outlet box provided with a door, a stationary glass panel mounted within the box independently of the door, a lever for operating the main and local alarm circuits disposed beneath the glass panel and arranged to project beyond one edge thereof, and means operatively connected with the stationary glass panel for normally rendering the main alarm circuit inoperative and for permitting operation of the same when the glass panel is broken.

3. A fire alarm apparatus having a main alarm circuit, a local alarm circuit, and means for controlling the operation of said circuits including an outlet box provided with a door, a stationary glass panel mounted within the box independently of the door, a lever for operating the local and main alarm circuits, and means connected with the stationary glass panel for normally rendering the main alarm circuit inoperative when the lever is manipulated to operate the local alarm circuit.

4. A fire alarm apparatus having a main alarm circuit, a local alarm circuit, and means for controlling the operation of said circuits including an outlet box provided with a door, a stationary glass panel mounted within the box independently of the door, and means for controlling the operation of said circuits including a lever, a spring pressed plunger, and connections between the plunger and stationary glass panel for normally rendering the main alarm circuit inoperative and for permitting its operation by means of the lever when the glass panel is broken.

5. A fire alarm apparatus having, in combination, a main alarm circuit, a local alarm circuit, and means for controlling the circuits comprising a box, a glass panel mounted upon the box, a lever for controlling the circuits, and means including a member pressing against the edge of the glass panel for normally rendering the main alarm circuit inoperative upon the actuation of the lever and for permitting operation of the main alarm circuit by means of the lever when the glass panel is broken.

VERNON DURBIN.
